UNITED STATES PATENT OFFICE.

HENRY H. VAUGHAN AND EDWARD CORNELIUS GAINES, OF MONTREAL, QUEBEC,
CANADA.

APPARATUS FOR LOADING AND UNLOADING RAILWAY CARS.

Application filed June 1, 1920. Serial No. 385,525.

To all whom it may concern:

Be it known that we, HENRY H. VAUGHAN, a subject of the King of Great Britain, and EDWARD CORNELIUS GAINES, a citizen of the 5 United States, both residents of the city of Montreal, have invented certain new and useful Improvements in Apparatus for Loading and Unloading Railway Cars; and we do hereby declare that the following is 10 a full, clear, and exact description thereof.

Our invention relates particularly to apparatus for loading and unloading railway cars the car supporting member of which is of the rocking cradle type, the 15 tilting motion of which is provided for by means of a rocking or rolling action thus necessitating a movable centre or pivot; some of the features of which, however, may be applied to a cradle tilting about a fixed 20 centre; and the invention is equally applicable to any type of mechanism having mechanical means similar to the above or so related that our invention can be advantageously applied. In the embodiment of 25 our invention hereinafter specifically described it is applied to the type of car unloading and loading apparatus in which the car is tipped or rocked endwise in order to discharge its contents of grain, coal or 30 other material in bulk out of one or both of the side doors when unloading, and to enable the lading to be piled up in bulk in each end of the car when loading.

To this end the invention consists of the 35 construction, combination and particular arrangement of parts hereinafter illustrated in the drawings and pointed out in the claims.

For full comprehension, however, of our 40 invention, reference must be had to the accompanying drawings in which similar reference characters indicate the same parts, and wherein:

Figure 1 is a longitudinal vertical sectional view of an apparatus constructed according to our invention for loading and unloading railway cars, a car being shown in position therein in dotted lines;

Figure 2 is a plan view thereof;

Figure 3 is a fragmentary plan view of the bumper mechanism for retaining the car in position upon the tiltable platform;

Figure 4 is a fragmentary longitudinal vertical sectional view illustrating one end 55 of the platform and its sub-structure;

Figure 5 is a transverse vertical sectional view of the apparatus;

Figures 6 and 7 are detail sectional views taken at right angles to each other of the differential mechanism forming a part of 60 the means for tilting the platform; and

Figure 8 is a detail sectional view of one of the racks for tilting the platform and illustrating its driving pinion in intermeshing relation with it.

The supporting structure of our unloader consists of a floor 2, side walls 3, and end walls 4 forming the power-plant chamber 5 and bin-space 6. A middle longitudinal pier 7 carries a track 8 on which rests the 70 rocker 9 of the cradle structure which has a platform 10 supporting the car indicated at 12 to be unloaded. The pier 7 is chambered as at 13 and communicates with chamber 5 and a bin or hopper 14 in chamber 6 75 is disposed with its discharge throat 15 over a conveyer 16. The ends of the tilting platform are accommodated by depressions 20 in the foundations and have wooden bumpers, 21 set rigidly on the bottoms 80 thereof. Bumper blocks 22 carried by the tiltable platform come into contact with these bumpers when the cradle is tilted to a maximum in either direction.

The cradle is tilted by a pair of arms 25 85 bearing racks 26 and having their upper ends pivotally connected at 27 to the ends of the cradle with their lower ends extending into the space 20. The racks carried by these arms are in intermeshing engagement with pinions 31 keyed on shafts 32 journaled in bearing 33, each of the arms being maintained in intermeshing relation with its respective pinion by rollers 34 carried in a guide frame 35, the guide frames being 90 in turn supported on shafts 32 between the bearing 33 and the pinions, and constructed and arranged to adjust themselves to the variable inclination of the arms. Each of the shafts 32 also carries rigidly thereon a 100 comparatively large bevel gear 36 and these bevel gears are in intermeshing relation with bevel pinions 37 of smaller diameter and respectively carried by a pair of axially aligned shafts 39 and 40 the adjacent ends 105 of which are operatively connected to a motor 50 by a differential mechanism adapted to automatically compensate for the varying velocities at which the arms 25 move and the shafts 39 and 40 rotate.

The differential mechanism we prefer to use consists of a worm 60 operatively connected to the shaft of the motor 50 and in intermeshing relation with a worm wheel 61. This worm wheel consists of a toothed ring 62 carried by a housing made up of two sections 63 and 64 connected together by bolts 65 and freely rotatable upon the adjacent ends of the shafts 39 and 40. Upon these shafts within the housing are rigidly mounted differential gears 66 and 67 the former being on shaft 39 and the latter on shaft 40. The differential gear 66 is in intermeshing relation with a plurality of differential pinions 68, three sets being shown in the embodiment illustrated, and the differential gear 67 is in intermeshing relation with a corresponding number of differential pinions 69. These pinions are mounted upon 20 transverse stub shafts 70 the ends of which are mounted in the sides of worm wheel 61. The differential mechanism is contained within a casing 71.

In the operation of this differential mechanism—upon the worm 60 being set in motion by the motor 50, the worm wheel is adapted to rotate moving with it the differential pinions, differential gears 66 and 67 and shafts 39 and 40 and the differential gear which is connected to the arm of the pair 25 having the lesser distance to travel of the two, or in other words the arm which is connected to the downward portion of the platform will rotate at a speed slower than that of the other differential gear, the differential pinions compensating for such difference in speed.

In order to keep the platform at each side of the car as clear as possible a door opener which forms a component part of the apparatus operates from a point above the door opening and may be swung entirely clear of this opening; and baffles acting as chutes for deflecting the lading from the car though one of its side doors are also adapted to be located clear of the portion of the platform adjacent the door opening when not in use.

The mechanism for opening the doors is carried by an upwardly extending lateral arm on the cradle structure constituted by a frame 110 rigidly mounted thereon and tilted in unison therewith. This door opening mechanism consists of a pair of door displacing arms fulcrumed as at 80 in the frame 110 at a point above the top of the door opening. The upper portion of each arm is constituted by a quadrantal rack 81 in intermeshing relation with an elongated pinion 82 mounted upon the shaft 83 such shaft being operatively connected to a motor 84 supported upon the top of the frame 110. The lower end of each arm is tapered downwardly and carries a box-like guiding member 88 the face of which is adapted to bear upon a grain door. The arms are constructed

and arranged to be swung in unison upon their points of fulcrum and are adapted to force the door inwardly relatively to the car thus freeing the nails. This movement is continued until the door is moved to position within the car adjacent the roof thereof and clear of the lading.

The baffles which are adapted to be inserted obliquely through the door opening and act as chutes for deflecting the lading being discharged and the mechanism for actuating them are located at one side of the cradle structure and on opposite sides of the door opening. The baffles are indicated at 90 and 91 respectively and with their actuating mechanism are alike in all respects and are movable on guideways on the frame 110 from position outside the car as illustrated in Figure 1 to position within the car as illustrated in dotted lines in Figure 2. The means for inserting each of the baffles into the car and withdrawing the same therefrom consists of a drum 140 mounted on a vertical shaft 114, a motor 144 operatively connected to the upper end of said shaft and adapted to drive the same and a rope or chain 141 wound around the drum and having its opposite end respectively connected to opposite ends of the baffle plate.

The cradle structure consists of the platform 10 and the rocker 9, the latter resting with its curved surface 170 upon its bed or rail 8. This cradle structure which is tiltable longitudinally is adapted to be locked in horizontal position by pins 171 and 172 located at the opposite ends thereof, the pins being supported in bearings upon the underside of the platform adjacent each end thereof and such pins being adapted to be moved into sockets 174 in the end walls 4. The pins are constructed and arranged to be actuated by a motor 175 located in the vicinity of the rocker 9 and operatively connected to the pins through shafts 176 and a train of gears 177, the rotation of the motor causing the pins to be fed axially relatively to the sockets.

The car to be tilted is adapted to be clamped in rigid position upon the platform by bumper mechanism. This bumper mechanism consists of a pair of bumpers 190 and 191 located at opposite ends of the platform and adapted to be actuated by a motor 192 located above the motor 175. Each bumper consists of a bumper arm 193 and a supporting arm 194 pivotally connected together as at 195. The opposite end of the arm 193 is fulcrumed on a shaft 196 in frames at the sides of the platform while the lower end of the arm 194 is fulcrumed as at 197 in a crosshead 198 slidably mounted in and capable of longitudinal movement relatively to the platform. This construction and arrangement of parts enables the bumper to be collapsed into position below the level

of the platform thereby avoiding interference with the movement of the car to and from the platform. The mechanism for moving the carriage longitudinally on the platform for the purposes of collapsing the arms consists of the motor 192 and longitudinal shafts 210 and 211, each of these shafts extending between the motor and its respective bumper and having threaded portions which through nuts 212 effect longitudinal movement of each of the crossheads 198. Springs 215 encircling rods 216 and constructed and arranged to yieldingly resist or counterbalance the lowering of the bumper arms.

What we claim is as follows:

1. The combination with a fixed horizontal supporting means, a tilttable member resting upon said means and tilttable thereon of

power means and means including differential mechanism connecting the power means to the opposite ends of the member for the purpose of tilting the same.

2. The combination with a fixed horizontal supporting means, a tilttable platform including a rocker resting upon said means and adapted to be rocked thereon of power means below the level of the platform and means including differential mechanism connecting the power means to the opposite ends of the rocker for the purpose of tilting the platform; door opening mechanism carried by the platform and constructed and arranged to present a clear space before the door of the car being unloaded.

3. The combination with a fixed horizontal supporting means, a tilttable platform including a rocker resting upon said means and adapted to be rocked thereon; power means below the level of the platform and means including differential mechanism connecting the power means to the opposite ends of the rocker for the purpose of tilting the platform, and a pair of baffles carried by the platform and constructed and arranged, when out of service, to assume positions on opposite sides of the door of the car being unloaded and parallel thereto.

4. The combination with a fixed horizontal supporting means, a tilttable platform including a rocker resting upon said means and adapted to be rocked thereon of power means below the level of the platform and means including differential mechanism connecting the power means to the opposite ends of the rocker for the purpose of tilting the platform, the platform having an upwardly extending lateral arm tilttable therewith and door opening mechanism mounted in said arm at a point above the top of the door of the car being unloaded.

5. The combination with a fixed horizontal supporting means a tilttable platform including a rocker resting upon said means and adapted to be rocked thereon, of power

means below the level of the platform and means including differential mechanism connecting the power means to the opposite ends of the rocker for the purpose of tilting the platform, the platform having an upwardly extending lateral arm tilttable therewith and door opening mechanism mounted in said arm at a point above the top of the door of the car being unloaded, a baffle mechanism carried thereby and constructed and arranged to, when out of service, present a clear space before the door of the car being unloaded.

6. The combination with a fixed horizontal supporting means, a tilttable platform including a rocker resting upon said means and adapted to be rocked thereon, of power means below the level of the platform and means including differential mechanism connecting the power means to the opposite ends of the rocker for the purpose of tilting the same, the platform having an upwardly extending lateral arm tilttable therewith and a baffle mechanism carried by said arm and constructed and arranged to, when out of service, present a clear space before the door of the car being unloaded.

7. The combination with a fixed horizontal supporting means, a tilttable platform including a rocker resting upon said means and adapted to be rocked thereon, of power means below the level of the platform and means including differential mechanism connecting the power means to the opposite ends of the rocker for the purpose of tilting the platform; door opening mechanism carried by the platform and constructed and arranged to present a clear space before the door of the car being unloaded, a baffle mechanism carried by said platform and constructed and arranged to, when out of service, present clear space before the door of the car being unloaded.

8. The combination with a fixed horizontal supporting means, a member adapted to be rocked upon said means, of means for rocking the same consisting of means connected at one end to the rocker member at opposite sides of the middle thereof, mechanism adapted to move the last mentioned means longitudinally in opposite directions, power mechanism and means including differential gear operatively connecting the power mechanism to the said mechanism for moving the tilting means.

9. The combination with a member adapted to be rocked, of means for rocking the same consisting of a pair of racks connected to the rocker member at opposite sides of the middle thereof, fixed means for guiding said racks, pinions intermeshing with the racks and adapted to move the racks longitudinally in opposite directions, power mechanism and means including differential gear operatively connecting the power mech-

anism to the pinions, said pinions being supported in fixed position.

10. In an apparatus of the type described the combination with a fixed flat body and a 5 cradle for supporting a car and resting upon and adapted to be rocked with rolling action upon the said flat bed, the combination with a member adapted to be rocked, a tiltable member supported upon said rocker member, of means for rocking said rocker member consisting of a pair of racks connected at their upper ends to the rocker member at opposite sides of the middle thereof, fixed 10 means for guiding said racks, pinions intermeshing with the racks and adapted to move the racks longitudinally in opposite directions, power mechanism and means including differential gear operatively connecting the power mechanism to the pinions, said 15 pinions being supported in fixed position.

11. In an apparatus of the type described the combination with a tiltable platform adapted to support a railway car thereon, of a laterally and upwardly projecting frame mounted upon said platform and tilt- 25 able in unison therewith, door opening mechanism mounted in said frame opposite the door of the car, and baffles mounted in said frame and located on opposite sides of the door opening mechanisms and adapted to be inserted into the car through its door opening.

In testimony whereof we have signed our names to this specification in the presence of two witnesses.

HENRY H. VAUGHAN.
EDWARD CORNELIUS GAINES.
